US0D1044324S

(12) United States Design Patent (10) Patent No.: US D1,044,324 S
(45) Date of Patent: * Oct. 1, 2024

(54) STORAGE RACK

(71) Applicant: Changzhou Wormhole Home Intelligent Technology Co., Ltd.,
Changzhou (CN)

(72) Inventor: Qingyi Li, Changzhou (CN)

(73) Assignee: Changzhou Wormhole Home Intelligent Technology Co., Ltd.,
Changzhou (CN)

() Term: 15 Years

(21) Appl. No.: 29/875,153

(22) Filed: Apr. 28, 2023

(51) LOC (14) Cl. 08-08

(52) U.S. Cl. D6/570
USPC ....

Assistant Examiner — Jeremy S. Swartz

(57) CLAIM

The ornamental design for a storage rack, as shown and described.

DESCRIPTION

FIG. 1 is a front, left, top perspective view of a storage rack showing my new design;

FIG. 2 is a back, left, bottom perspective view thereof;

FIG. 3 is a front view thereof;

FIG. 4 is a back view thereof;

FIG. 5 is a right view thereof;

FIG. 6 is a left view thereof;

FIG. 7 is an enlarged top view thereof;

FIG. 8 is an enlarged bottom view thereof;

FIG. 9 is an enlarged view of the encircled area 9 of FIG. 2;

FIG. 10 is an enlarged view of the encircled area 10 of FIG. 3; and,

FIG. 11 is an enlarged view of the encircled area 11 of FIG. 5.

The broken lines in the drawings depict portions of the storage rack that form no part of the claimed design; the dash-dot broken lines in the figures demarcate boundaries and form no part of the claimed design.

1 Claim, 8 Drawing Sheets
